UNITED STATES PATENT OFFICE.

HOYT CATLIN, OF FAIRFIELD, CONNECTICUT, ASSIGNOR TO THE BRYANT ELECTRIC COMPANY, OF BRIDGEPORT, CONNECTICUT, A CORPORATION OF CONNECTICUT.

ELECTRIC SWITCH.

1,393,612.

Specification of Letters Patent. Patented Oct. 11, 1921.

Application filed March 2, 1921. Serial No. 449,058.

To all whom it may concern:

Be it known that I, HOYT CATLIN, a citizen of the United States of America, residing at Fairfield, in the county of Fairfield and State of Connecticut, have invented certain new and useful Improvements in Electric Switches, of which the following is a specification.

My invention relates to electric switches, and particularly to rotary snap switches. The object of my invention is to provide an improved mounting for the operating handle or thumb piece, for the purpose of not only preventing injury to the switch mechanism as the result of attempts to operate the same in the wrong direction, but in order to secure proper indication of the connections established by the switch under all conditions.

20 In the accompanying drawings—

Figure 1 is a plan of a switch having mounted thereon a handle, to which my invention is applied in one form;

25 Fig. 2 is a side elevation of the switch showing the handle elements in vertical section;

Fig. 3 is a section on the line 3—3, Fig. 2; and

30 Figs. 4 and 5 are similar views, but showing the handle in different positions.

The one-way rotary snap switch mechanism of the electric fitting to which my invention is shown applied, may be of any desired construction, and it is therefore not 35 illustrated, except that the spindle 6 upon which the mechanism is mounted is indicated in certain of the figures. A casing 7 of usual type incloses the switch mechanism and bears on its upper surface legends 8 to indicate the 40 connections established by the switch bar in its various positions. The switch indicated is of the type known as a heater switch for controlling various connections to the resistance units of a heating device, such for 45 instance as that used in an electric cooking range, or the like. In switches of this character, the mechanism is commonly rotatable only in one direction, and its reverse rotation is apt to injure the springs which 50 effect its snap action, or otherwise derange the mechanism.

To actuate the switch and at the same time not only to safeguard it against injury by attempt at reverse rotation, but also to maintain the switch indicator in proper position

with relation to the legends 8, I mount on the spindle the operating device to which my invention is particularly directed. This device comprises a sleeve 9 having an operating connection 10, of any sort, with the spindle 6. Freely swiveling on the sleeve, except for the lost motion engagement hereinafter mentioned, is a thumb-piece or handle 11, through which the sleeve passes. Moving therewith, and here shown integral therewith, is a pointer 12, the position of which with respect to the legends 8 on the casing 7, indicates the connection established in the various switch positions. The endwise escape of the handle from the sleeve 70 is prevented by a washer 13 seated against a shoulder at the outer end of the sleeve and retained by the rolled-over edge of the neck 14 extending beyond the shoulder. This washer bears freely against the bottom of 75 the well 15 in the outer face of the thumb-piece, thus detaining the latter while at the same time permitting it to freely rotate. After the operating connection at 10 has been effected between the sleeve 9 and spindle 80 6, the parts are held in assembled position by any suitable securing means, such as a screw 16 taking into the upper end of the spindle 6 and bearing against the outer end 85 of the sleeve 9.

The above mentioned lost motion engagement between the handle 11 and sleeve 9 is secured as follows: On the lower face of the handle 11 is a countersunk boss 17 with an inwardly projecting lug 18. Seated 90 against the bottom of this countersink is a lug 19 fast on the sleeve 9. Normally maintaining these lugs 18 and 19 in engagement, as indicated in Fig. 3, is a slightly tensioned coil spring 20 surrounding the sleeve and 95 accommodated in the chamber 21 in the body of the handle 11. One end 22 of this spring engages the lug 19 on the sleeve, while its other end 23 engages a slot 24 in the handle 11.

100 While obviously an actuating connection between the handle 11 and the switch spindle 6 is thus established, provided the handle is rotated clockwise (Fig. 4) in the manner indicated by the arrow X in Fig. 1, since 105 the lug 18 on the handle and the lug 19 on the sleeve are in engagement, it is equally obvious that upon contra-clockwise rotation (Fig. 5) the lug 18 on the handle moves away from the lug 19 on the sleeve and 110

leaves the spindle 6 unaffected. This rotation, however, further tensions the spring 20, so that upon release of the handle it at once snaps back to the position in which the lugs 18 and 19 are in engagement. This of course restores the pointer 12 to proper indicating position with respect to the legends 8 on the casing. The extent of the arc through which the handle may be inoperatively rotated in contra-clockwise direction, may be varied as necessary. It should be sufficient, however, to prevent engagement between the lugs 18 and 19 on a single manipulation of the handle; something over half a turn is ordinarily sufficient since it is practically impossible for the operator to turn the handle through a greater arc than this without releasing the handle to take a fresh grip. Immediately upon such release the handle 20 returns to its original position. The extent of the arc on the other hand should not be so great as to put too great a strain on the spring 20.

Various modifications of construction will 25 readily occur to those skilled in the art. I wish to call particular attention, however, to the fact that the construction illustrated not only affords an assembly unit, which is itself readily assembled and may be readily 30 mounted on a switch spindle as a unit, but it also affords protection against reverse rotation of the switch, while at the same time maintaining the indicator in proper position with respect to the legends on the casing.

35 I claim—

1. A rotary snap switch comprising a one-way rotary snap switch mechanism, legends for indicating the connections established by the switch, a handle having a one-way

connection with the switch mechanism, an 40 associated pointer coöperating with the indicator legends, and spring means for returning said handle and pointer to predetermined position with respect to the switch mechanism after rotation of said handle in 45 opposition to said one-way connection.

2. A handle unit for a rotary snap switch, such unit comprising a carrier adapted to positively engage a switch spindle, a handle swiveling on said carrier, a one-way connection 50 between said handle and carrier, and means for automatically returning said handle to position after rotation in opposition to said one-way connection.

3. A handle unit for a rotary snap switch 55 comprising a rotary carrier, a handle swiveling on said carrier, means establishing a one-way operating connection between said parts, and a spring normally holding said one-way operating parts in engagement in 60 predetermined relative position.

4. A handle unit for a rotary snap switch comprising a rotary carrier, a handle swiveling on said carrier, means establishing a one-way operating connection between said parts, 65 and a spring normally holding said one-way operating parts in engagement, in combination with a pointer associated with said handle and moving therewith in the direction wherein said one-way connection operates, and also in opposite direction in 70 opposition to said spring, together with stationary indicating legends with which said pointer is associated.

In testimony whereof I have signed my 75 name to this specification.

HOYT CATLIN.
